REFRIGERATOR CAR

Arthur A. Helwig, Chicago, Ill., assignor, by mesne assignments, to Standard Railway Refrigerator Company, a corporation of Delaware

Application August 21, 1939, Serial No. 291,109

1 Claim. (Cl. 62—17)

This invention relates to refrigerator cars used to transport perishable commodities at a predetermined temperature. The essential features of a refrigerator car are an insulated body to prevent or retard ingress of heat during warm weather and egress of heat during cold weather and a cooling means and a heating means to be used during warm and cold weather respectively.

This invention applies particularly to cars in which the cooling means, preferably containers for water ice, eutectic ice, brine or dry ice, are disposed immediately below the roof of the car. The lading is supported in spaced relation to the floor by a foraminous rack. Flues, preferably associated with the side walls of the car, communicate between the cooling means and the space under the floor rack to provide a path for the circulation of air. The path is from the cooling means downwardly through the aforementioned flues, through the space under the floor rack, upwardly through the lading compartment thereby cooling the lading, and finally to the cooling means from where the cycle is repeated.

An object of the invention is to reinforce and stiffen the refrigerant container by corrugating some or all of the walls thereof; the term "walls" being intended in a broad sense so as to include the top and bottom, as well as the vertical walls. A further object is to place the container with its corrugated walls substantially in contact with a wall of the car or with an adjacent container, thereby securely supporting the container as well as providing flues for air circulation between the container and the aforementioned wall or adjacent container.

Another object of the invention is to brace adjacent tanks against each other and provide air flues therebetween. I accomplish this by corrugating the adjacent sides of both containers and having the outwardly projecting parts of the corrugations in one container in contact with the similar parts of the adjacent container, thereby providing air flues between the inwardly projecting parts of the corrugations in the container walls.

Another object of the invention is to increase the area of contact of the air with the cold surface of the refrigerant container. Corrugations which I claim as my invention have a considerably greater surface than a flat surface. A further object is to increase the refrigerant capacity of the containers without increasing the height or width of the car. The outwardly projecting parts of the corrugations provide in-

creased space for the accommodation of refrigerant.

In the drawing:

Fig. 1 is a transverse section of a refrigerator car embodying my invention.

Fig. 2 is a longitudinal section of the upper portion of the car shown in Fig. 1 as indicated by the line 2—2 of Fig. 1.

Figs. 3 and 4 are fragmentary sectional views of portions of the car as indicated by the lines 3—3 and 4—4, respectively, in Fig. 1.

The general parts of the refrigerator car shown are insulated roof 2; side walls 3; floor 4; hatch 5; refrigerant container 6; side wall flue 7; foraminous floor rack 8 and space 9 between rack 8 and floor 4. A refrigerant container 6 is positioned directly below the roof 2 and adjacent the side wall 3. A drip pan 12 is provided below the container 6 and a partition 14 is secured in an upstanding position at the edge of the drip pan 12. The drip pan 12 and partition 14 cooperate with the roof 2 and side wall 3 to form an enclosing structure 11 around the container 6, an air inlet opening 15 being provided by spacing the partition 14 from the roof 2. An air discharge opening 17 which leads to the flue 7 is formed by spacing the drip pan 12 from the wall 3.

Air circulation is as follows: Air in the lading compartment 18 is warmed by contact with the lading and rises to enter the enclosing structure 11 through the air inlet opening 15. The air is cooled by contact with the cold refrigerant container 6 and falls by reason of its greater density through the discharge opening 17 and flue 7 to the space 9 whence it rises through the rack 8 to the lading compartment 18. Cars of this type usually have a row of refrigerant containers near each wall and directly below the roof so that air flowing from the lading compartment flows between the containers disposed on opposite sides of the car.

In the form of my invention shown, the refrigerant container 6 comprises a bottom 20; a top 21; side walls 22—23 and end walls 24. The outwardly projecting parts 26 of the corrugations 27 in the bottom 20 of the container 6 are in contact with the drip pan 12, thereby providing flues 28 between the inwardly projecting parts 30 of the corrugations and the drip pan 12. The outer parts 35 of the corrugations 36 in the top 21 are in contact with the ceiling 38 and the spaces between the inwardly projecting parts 39 and the ceiling 38 form flues 40 for the circulation of air. The outwardly projecting parts 45

of the corrugations 46 in the end walls 24 of adjacent containers 6 are in contact while the spaces defined by the inwardly projecting parts 49 of the end wall corrugations 46 form flues 50 for air circulation. The outwardly projecting parts 35 of the corrugations 56 in the side wall 22 of the container 6 are in contact with the lining 57 of the side wall 3 of the car, thereby forming the flues 59 between the inwardly projecting parts 60 of the corrugations 56 and the lining 57. The outwardly projecting parts 65 of the corrugations 66 in the side wall 23 are in contact with the partition 14, thus forming the flues 65 between the inwardly projecting parts 68 of the corrugations 66 and partition 14.

In Fig. 2, the right half of the container 6 is shown formed with sinuous corrugations 75, whereas the left half is shown with the inwardly projecting parts of the corrugations 77 embodying a flat portion 78 of considerable width. It is not intended that containers should be constructed strictly in accordance with Fig. 2, but that the containers may be formed with corrugations as shown either on the right or on the left. It is also intended, for example, that the end walls 24 of the container may be formed with one type of corrugation, while the bottom 20 of the container may be formed with another type of corrugation, or that each wall may have a different type of corrugation. The advantage advanced for the corrugations 77 shown on the left is that the size of the air flues is very considerably increased but at a sacrifice of strength. The type of corrugation used would depend upon the requirements as to both strength of container and area of flue required.

The arrows in Fig. 1 show the path of the air circulation. A portion of the air flows through the flues 40 above the container and the flues 59

5 at the side 22 of the container, another portion flows through the flues 67 at the side 23 and the flues 29 at the bottom 20 of the container, and still another part flows through the flues 50 between the containers. All of the circulating air converges into the side wall flue 7, flows into the space 9 under the floor rack 8, then to the lading compartment and finally back to the refrigerant compartment 11 whence the cycle is 10 repeated.

The accompanying drawing illustrates the preferred form of the invention, though it is to be understood that the invention is not limited to the exact details of construction shown and described, as it is obvious that various modifications thereof, within the scope of the claim, will occur to persons skilled in the art.

I claim:

In a refrigerator car having a lading compartment, a roof, a wall and a flue adjacent said wall leading from the upper to the lower part of the car, a pair of refrigerant containers each disposed adjacent said wall and near said roof, the adjacent walls of said containers being formed with substantially horizontal outwardly projecting corrugations, the corrugations of one of the containers being in contact with the corrugations of the other container and the part of the walls between said corrugations being spaced apart to form a plurality of ducts communicating at the outer ends thereof with the upper part of said flue, said car being arranged to provide air communication between the upper part of the lading compartment and the inner ends of 30 said ducts, whereby air flows from the lading compartment through said ducts and, upon being cooled, flows downwardly through said flue to the lower part of the car.

ARTHUR A. HELWIG.
